UNITED STATES PATENT OFFICE.

RICHARD PAUL HEMMING, OF PHILADELPHIA, PENNSYLVANIA, ASSIGNOR
TO GEORGE W. ENNIS & CO., OF SAME PLACE.

DESIGN FOR A RUG.

SPECIFICATION forming part of Design No. 16,769, dated July 6, 1886.

Application filed May 27, 1886. Serial No. 203,475. Term of patent 3½ years.

To all whom it may concern:

Be it known that I, RICHARD PAUL HEMMING, a citizen of the United States, residing at Philadelphia, in the county of Philadelphia and State of Pennsylvania, have invented and produced a new and original Design for a Rug; and I do hereby declare that the photographic print accompanying this specification conveys to any one skilled in the art a clear understanding of the same, and is sufficient to enable such persons to use my invention.

The leading features of my design consist in a triple-panel center, the center panel in form of an oval, the end panels circular, having the appearance of being overlapped by the ends of the center oval panel. The center oval and end panels are ornamented by a

floral representation, the whole surrounded by an ornamental border, as shown. The print shows only three-fourths of the whole design. The end not shown is exactly like the end that is shown.

What I claim as my invention is—
The design for a rug, consisting of a center panel in form of an oval having the appearance of overlapping the circular end panels, the panels ornamented by a floral representation, the whole surrounded by an ornamental border, as shown in the photographic print.

R. PAUL HEMMING.
